(74) Attorney, Agent, or Firm — Dickinson Wright PLLC;
Andrew D. Dorisio

(57) **CLAIM**

The ornamental design for a golf club head, as shown and described.

DESCRIPTION

Figure 1.1 is a front perspective view;

Figure 1.2 is a front elevational view;

Figure 1.3 is a left side view;

Figure 1.4 is a rear elevational view;

Figure 1.5 is a top plan view;

Figure 1.6 is a bottom plan view;

Figure 1.7 is a rear perspective view;

Figure 2.1 is a front perspective view;

Figure 2.2 is a front elevational view

Figure 2.3 is a left side view;

Figure 2.4 is a rear elevational view;

Figure 2.5 is a top plan view;

Figure 2.6 is a bottom plan view;

Figure 2.7 is a rear perspective view;

Figure 3.1 is a front perspective view;

Figure 3.2 is a front elevational view;

Figure 3.3 is a left side view;

Figure 3.4 is a rear elevational view;

Figure 3.5 is a top plan view;

Figure 3.6 is a bottom plan view; and

Figure 3.7 is a rear perspective view.

(Continued)

The broken lines on the drawing figures forms no part of the claimed design.
